UNITED STATES PATENT OFFICE.

WILLIAM S. REECE, OF PORTLAND, OREGON.

VALVE

1,372,547.

Specification of Letters Patent. Patented Mar. 22, 1921.

Application filed December 7, 1918. Serial No. 265,637.

To all whom it may concern:

Be it known that I, WILLIAM S. REECE, a citizen of the United States, residing at Portland, in the county of Multnomah and State of Oregon, have invented new and useful Improvements in Valves, of which the following is a specification.

This invention relates to new and useful improvements in automatic valves for oil burning furnaces and the principal object of the invention is to provide means for regulating the flow of oil and steam to the burners of the furnace so as to maintain a uniform steam pressure in the boiler.

Another object of the invention is to provide means for adjusting the oil valves to meet the variations of pressure in the oil supply and to yieldingly connect the oil valves to the stems so as to prevent injury to the parts.

In describing my invention in detail, reference will be had to the accompanying drawing wherein like characters denote like or corresponding parts throughout the several views, and in which:

Figure 1 is a central longitudinal section through the apparatus.

Fig. 2 is an enlarged sectional view through the oil valves.

As shown in these views the invention consists of the oil casing 1 and the steam casing 2 which are connected together by a spring cylinder 3 and the arm 4.

The oil casing is provided with a pair of valve seats 5 spaced apart and the inlet for the oil is located between these seats, so that the oil passes in two streams in opposite directions from said seats. 6 indicates a double shouldered valve member having the valves 7 and 8 connected therewith and these valves are adapted to engage the seats 5. It will be seen the valve 8 is of less diameter than the valve 7 so that the pressure of the oil tends to open the valves.

The steam casing is similarly formed with the exception that the inlet of steam is in an opposite direction through the valve seats and the outlet for the steam leads from the space between the valves 9 and 10 of the double shouldered valve member. By this means the pressure of the steam tends to hold the steam valves on the seats. I prefer to so construct the oil valves that their combined areas are greater than those of the steam valves so that the oil valves may

close in advance of the steam valves. This permits the oil valves to work closer to the seats.

The bottom of the steam casing is closed by a removable bonnet 11 and this bonnet is so made as to form a cylinder 12 to receive a compensating spring 13 which acts upon a piston 14 having its stem 15 adjustably secured to the lower steam valve 9. A second piston 16 engages the lower end of the spring and is carried by a set screw 17 passing through the end of the cylinder. The upper part of the steam casing is provided with a removable part 18, which together with the said casing forms a steam chamber. The upper end of this part 18 is provided with a flange 19 to receive the flange 20 formed on the lower end of the cylinder 3. These flanges are bolted together by the bolts 21 and they form a diaphragm chamber 22. A diaphragm 23 is placed in said chamber and is held in position by being clamped between the flanges. The steam chamber is in communication with the chamber 22 by means of the ports 24 and the plunger 25 has sliding movement in a hole 26 formed in the flange 19 between the steam chamber and diaphragm chamber. This plunger is secured to the end of a stem 27 connected with the upper face of the valve 10.

The piston 28 has limited movement in the lower end of the cylinder 3 and the curved lower face of said piston projects into the diaphragm chamber so as to contact with the diaphragm. An annular recess 29 is formed in the lower end of the cylinder and the piston is provided with a flange 30 which engages said recess. By this means the movement of the piston is limited. 31 indicates a compensating spring located in the cylinder 3 and engaging the piston 28. This spring may be adjusted by means of the piston 32 carried by the screw threaded stem 33 passing through the top of the cylinder and provided with a handle 34. The piston 28 is provided with a stem 35 which passes through the stem 33 and through the removable bottom 36 of the oil casing, and is connected with the oil valves. The bottom 36 carries a packing gland 37.

As before stated the oil valves seat themselves before the steam valves and to prevent injury to the parts I yieldingly connect said oil valves to the stem 35. To do this

I provide a core 38 having its lower end provided with a screw threaded socket 39 to receive the screw threaded end of the stem 35. This socket forms a shoulder 40 upon which is seated the coiled spring 41. The valve member 6 is of tubular form so as to surround said spring and core and to slidably engage said core and sleeve. The spring engages with the lower face of the 10 valve 8 and tends to hold the valve member in its highest position. The core passes through said valve 8 and the valve member is adjustable on the core by means of the nut 42 engaging with the projecting end 15 of the core. It will thus be seen that the valve member is yieldingly held to the core by the spring. The upper end of the core is flattened as at 43 and this flattened end engages a slot 44 in the end of the stem 45 which is provided with a handle 46. This stem passes through the upper end of the oil casing. By turning the handle 47 the valve member may be adjusted on the core. It will thus be seen that the stem acting 25 upon the diaphragm will automatically control the flow of oil to the burners. The oil entering the valve between the two seats relieves the pressure on the gland 37. It will be seen that the steam acting on the 30 large valve 9 will tend to hold the valves 9 and 10 upon the seats and also tends to counteract the opening of the oil valves.

Should it become necessary to close the steam valves in advance of the oil valves the 35 operator may remove the bonnet 11 and adjust the seats more closely to the diaphragm, thus the steam valves will reach their seats while the diaphragm will pass on until the piston 28 reaches its seat. In 40 this case there will be a space between the plunger 25 and the diaphragm which will be taken up as the steam pressure diminishes in the boiler. This will permit the compensating spring to force the diaphragm 45 into contact with the plunger, and thus open the valves.

It is thought from the foregoing description that the advantages and novel features of my invention will be readily apparent.

50 I desire it to be understood that I may make such changes in the construction and in the combination and arrangement of the

several parts, provided that such changes fall within the scope of the appended claims.

Having thus described the invention I 55 claim:—

1. A device of the class described comprising an upper oil casing and a lower steam casing, a pair of valve seats in each casing, means for delivering the oil between 60 the seats of the oil casing and the steam above and below the seats of the steam casing, double shouldered valves engaging said seats, the lower shoulder of each valve being of greater diameter than the upper shoulder, 65 a diaphragm chamber in communication with the steam casing, a diaphragm in said chamber, stems connected with the said valves and engaging said diaphragm and spring means for holding the stems in engagement with the diaphragm.

2. A device of the class described comprising an upper oil casing and a lower steam casing, a pair of valve seats in each casing, means for delivering the oil between 75 the seats of the oil casing and the steam above and below the seats of the steam casing, double shouldered valves engaging said seats, the lower shoulder of each valve being of greater diameter than the upper shoulder, 80 a diaphragm chamber in communication with the steam casing, a diaphragm in said chamber, stems connected with the said valves and engaging said diaphragm, spring means for holding the stems in engagement 85 with the diaphragm and means for yieldingly connecting the oil valve with the stem.

3. A device of the class described comprising an upper oil casing and a lower steam casing, a pair of valve seats in each 90 casing, means for delivering oil between the seats of the oil casing and the steam above and below the seats of the steam casing, double shouldered valves engaging said seats, a core slidably connecting with the 95 oil valves, a spring located between the valve and core, a stem having screw threaded connection with the core, means for adjusting the core on said stem, a stem connected with the steam valve, a chamber connected with 100 the steam casing and a diaphragm therein engaging the stems.

In testimony whereof I affix my signature.
WILLIAM S. REECE.
